DESIGN FOR A BOWLING BALL CARRIER OR THE LIKE

Harry H. Podjus, Chicago, Ill., assignor to The
Brunswick-Balke-Collender Company, Chicago,
Ill., a corporation of Delaware

Application April 2, 1945, Serial No. 118,835

Term of patent 14 years

(CL. D34—5)

To all whom it may concern:

Be it known that I, Harry H. Podjus, a citizen of the United States, residing in the city of Chicago, in the county of Cook, State of Illinois, have invented a new, original, and ornamental Design for a Bowling Ball Carrier or the like, of which the following is a specification, reference being had to the accompanying drawing, forming a part thereof.

Figure 1 is a front elevational view of a bowling ball carrier or the like showing my new design;

Figure 2 is a top plan view thereof;
Figure 3 is an end view thereof looking at the lefthand end of Figure 1.

The dominant features of the design are shown in full lines.

I claim:

The ornamental design for a bowling ball carrier or the like, as shown and described.

HARRY H. PODJUS,
